CLAIM

The ornamental design for a ballpoint pen, as shown and described.

DESCRIPTION

FIG. 1 is a perspective view of a ballpoint pen showing my new design;

FIG. 2 is a front view thereof;

FIG. 3 is a bottom view thereof; the top view is a mirror image of FIG. 3.

FIG. 4 is a rear view thereof;

FIG. 5 is a right side view thereof;

FIG. 6 is a left side view thereof;

FIG. 7 is a further front view thereof, showing the cap removed and placed on the opposite end of the ballpoint pen; and,

FIG. 8 is a bottom view thereof.
